UNITED STATES PATENT OFFICE.

TALBOT G. MARTIN, OF CHICAGO, ILLINOIS, ASSIGNOR TO AUTOMATIC ELECTRIC COMPANY, OF CHICAGO, ILLINOIS, A CORPORATION OF ILLINOIS.

REPEATER FOR AUTOMATIC TELEPHONE SYSTEMS.

1,314,454.

Specification of Letters Patent. Patented Aug. 26, 1919.

Application filed February 9, 1916. Serial No. 77,247.

To all whom it may concern:

Be it known that I, TALBOT G. MARTIN, a citizen of the United States of America, and a resident of Chicago, county of Cook, 5 and State of Illinois, have invented certain new and useful Improvements in Repeaters for Automatic Telephone Systems, of which the following is a specification.

My invention relates to automatic telephone systems and more particularly to such systems as comprise a plurality of exchanges between which connections may be established through the medium of automatic switches. In these systems the various exchanges are interconnected or linked together by trunk lines. A calling subscriber in one exchange, desiring connection with a subscriber in a second exchange, manipulates the impulse sending device with which he is 10 provided to operate a switch or switches at his exchange, whereby a trunk line is selected which extends to the desired second exchange. At the second exchange certain automatic switches are accessible to the 15 trunk line whereby the connection may be extended through to the line of the desired subscriber.

It is customary, in order to obviate the necessity of using more than two conductors in a trunk line and in order to secure efficient transmission of the operating impulses, to 20 insert a so-called repeater in each trunk line. A repeater in common use consists essentially of a pair of bridges across the trunk line, the two conductors of which have their metallic continuity broken between the 25 bridges by means of condensers. The first bridge contains a controlling relay which operates when the trunk is seized to ground 30 the third conductor in the well known manner, and to close a circuit including the other bridge which extends to the distant exchange. Interruptions of the circuit of the 35 controlling relay will be repeated in the circuit to the distant exchange in a manner readily apparent.

It will be clear without going into further details that in order to secure an efficient talking circuit by way of a trunk line and 40 repeater, the capacity of the condensers and the impedance of the bridges must be as high as is practicable. The impedance of the second bridge may be made high without trouble but the impedance of the controlling 45 relay bridge and the capacity of the con-

densers are both limited by certain features incidental to the sending of operating impulses over the trunk line, as will appear more clearly hereinafter.

It is the principal object of my invention 60 to provide, in a repeater having condensers of moderate capacity and a controlling relay designed to secure the most efficient operation without regard to high impedance, means whereby the capacity of the condensers and the impedance of the controlling 65 relay bridge may both be increased during conversation.

Further objects relate to the circuit arrangements by which the principles of my 70 invention are incorporated into repeaters of well known type and construction to form a simple and efficient apparatus.

To accomplish the foregoing and other useful ends my invention comprises means 75 which will be hereinafter set forth and fully explained, reference being had to the accompanying drawings.

In the drawings, Figures 1, 2 and 3, taken in order with the lines at the ends thereof 80 in alinement, represent diagrammatically a complete circuit connection between a calling substation A and a called substation A', the two substations terminating in separate exchanges in a system embodying the principles of my invention. The said connection has been established through the medium of the individual line switch C, selector switch E, repeater F, trunk line 78-79, selector switch E', and connector switch H. 90

Referring now to Fig. 1, the substation A may be of any suitable or approved type, and as herein represented comprises the receiver 3, transmitter 4, ringer 5, and condenser 6. Being an automatic substation, 95 it is also provided with an impulse sending device which may be of the type disclosed in British patent to S. G. S. Dicker, No. 29,654 of 1910. The impulse sending device consists essentially of the impulse 100 springs 7 controlled by the impulse wheel 8 through the medium of a finger hole dial (not shown).

The individual line switch C and the master switch D are of the general type of 105 line and master switches disclosed in British patent to R. W. James, No. 26,301 of 1906; being, however, more nearly of the particular type disclosed in British patent to T. G. Martin, No. 1419 of 1910. Among other de- 110

tails the line switch C comprises a plunger (not shown) attached to a so called plunger arm controlled by the magnet 10. The magnet 10 has two windings, a pull-in winding 5 13 and a cut-off or holding winding 12. The pull-in winding, when energized, is strong enough to operate both the plunger arm 9 and the cut-off armature 11; while the cut-off winding 12 is only strong enough to operate the cut-off armature and to maintain the plunger arm 9 in an operated position after it has been operated by the pull in winding 13. The latter winding is controlled through the medium of the line relay 14 which in turn is controlled from the substation A. When the plunger arm is operated, the plunger is forced into a bank of contact springs, forcing the springs 15, 16, 17, and 18 into engagement, respectively, with contacts 19, 20, 21, and 22. Although only one set of springs and contacts (15-22, inclusive) is shown, it is understood that each line switch is provided with a plurality of such sets, each set forming the terminal of a trunk line 25 extending to a selector switch. Each trunk line is connected in multiple to corresponding terminals in the banks of all the line switches controlled by the master switch D. The function of the master switch, as is well known, is to maintain the plungers of all idle line switches of its group in position before the terminals of an idle trunk line.

The selector switch E is of the general type of selector switch disclosed in United States Letters Patent No. 815,321, granted March 13, 1906, to Keith, Erickson and Erickson; being, however, of the particular type shown in British patent to the Automatic Telephone Manufacturing Company, No. 2543 of 1914. Among other details the selector E comprises a bank of contacts arranged in horizontal rows or levels, which contacts are adapted to be engaged by a set of wipers 23, 24, and 25 carried upon a shaft 45 (not shown) which has a vertical movement controlled by the vertical magnet 27, and a rotary movement controlled by the rotary magnet 28. The operation of the various parts of the switch is controlled through the medium of the double wound line relay 26. Means for permitting the switch to be restored to normal position is provided in the release magnet 120, which, upon energizing, withdraws the retaining pawls from the shaft. The contacts 74 and 77 make against their respective springs only when the shaft 50 has been raised one or more steps from its lowest position. The relays 30 and 32 are slow acting, that is, they retain their armatures for an instant after their energizing circuits are broken.

The repeater F (Fig. 2) is of the general type of repeater disclosed in United States Letters Patent No. 1,136,912, granted April 65 20, 1915, to T. G. Martin. The circuits are

modified, however, and certain parts are added in order to enable it to operate according to the principles of my invention. The functions of the various relays and the operation will be described in detail herein- 70 after.

The trunk line 78-79 terminates at the distant exchange in the selector switch E' which is in all essential particulars the same as selector switch E, already described. 75

Accessible to the selector E' I have shown a connector switch H (Fig. 3) which is of the general type of connector switch disclosed in United States Letters Patent No. 815,176, granted March 13, 1906, to Keith, 80 Erickson and Erickson; being, however, more nearly of the particular type shown in British patent to the Automatic Telephone Manufacturing Company, No. 2270 of 1914. Among other details, the connector H comprises a bank of contacts arranged in horizontal rows or levels, which contacts are adapted to be engaged by a set of wipers 88, 89, and 90, carried upon a shaft (not shown) which has a vertical movement controlled by 85 the vertical magnet 83, and a rotary movement controlled by the rotary magnet 84. The usual side switch comprising the wipers 115, 116, 117, and 118 is controlled by the private magnet 95 in the well known manner. The operation of the various parts of the switch is controlled through the medium of the double wound line relay 82 which also serves to feed talking current to the calling line. The called line is provided with talking current through the windings of the double wound answering bridge relay 87 which operates, when energized, to reverse the battery connections to the trunk conductors 113 and 114. The ringing relay 102 affords means for projecting ringing current over a called line to signal the called subscriber. Means for permitting the connector to be restored to normal position is provided in the release magnet 86, which, upon 95 energizing, withdraws the retaining pawls from the shaft, and returns the side switch wipers to their first position. The contacts 108^a and 109^a make against their respective springs only when the shaft has been raised 110 one or more steps from its lowest position. Relays 85 and 93 are slow acting.

Substation A' and the individual line switch C' are similar to substation A and its individual line switch C, which have already 115 been described.

For supplying operating and talking current I have shown two batteries indicated by reference characters B and B' and each having its positive terminal grounded. I 120 have shown a generator R for supplying ringing current and an interrupter 103 for intermittently breaking the operating circuit of the ringing relay. At Q I have shown a busy signaling machine. 130

Having given a general description of the apparatus, I will now describe the operation of a system embodying the principles of my invention. For the purposes of this explanation it will be assumed that the subscriber at substation A in one exchange, desired to establish connection with the subscriber at substation A' in another exchange. Inasmuch as a great deal of the automatic apparatus shown herein is old and well known in the art, having been fully described in the publications above referred to, its operation will be described in a more or less general manner, the details being given only where they have to do with the operation of my invention.

Referring now to Fig. 1, the subscriber at substation A, upon removing his receiver to initiate the call, completes an energizing circuit for the line relay 14 of the line switch C in an obvious and well known manner. Upon attracting its armature, the line relay 14 completes an energizing circuit for the pull-in winding 13. The pull-in winding, upon energizing, attracts the plunger arm 9 and the cut-off armature 11; the former, by means of its plunger, forcing the springs 15-18, inclusive, into engagement, respectively, with contacts 19-22, inclusive; and the latter disconnecting the line conductors 1 and 2 from their battery connections in the line switch.

By the engagement of springs 15 and 18 with contacts 19 and 22, respectively, the line conductors 1 and 2 are extended to the double wound line relay 26 of the selector E. The line relay thereupon is energized over the previously mentioned circuit through substation A and, upon attracting its armature, completes a circuit from ground at G⁷ to the slow acting relay 30 and thence to battery B. Relay 30, upon energizing, completes a holding circuit extending back to the line switch C over the following path: ground at G³, contacts springs 31, contact 20, spring 16, and holding winding 12 to battery B. Although the circuit of the line relay 14 has already been broken it retains its armature long enough to allow the above holding circuit to be established. A branch of the holding circuit extends by way of conductor 201 to multiple test contacts in the banks of connectors having access to the line of substation A where, by a ground potential on these test contacts, the said line is made busy.

The foregoing operations have all occurred in response to the removal of the receiver from the hook. The subscriber at substation A may now operate his dial in accordance with the first digit of the desired number, thereby breaking the continuity of his loop a corresponding number of times. As a result of these interruptions the line relay 26 is deenergized a like number of times,

sending an impulse at each deenergization from ground at G⁷ through the slow acting relay 32, and the vertical magnet 27 in series to battery B. The vertical magnet, in response to these impulses, steps up the shaft until the wipers stand opposite the horizontal level in which are located contacts which are terminals of trunk lines extending to the desired exchange. The relay 32, being slow acting, retains its armature during the series of impulses and closes a circuit for the test relay 33, which latter relay prepares a circuit for the rotary magnet and locks itself from ground G³. At the end of the series of impulses the relay 32 deenergizes thereby completing a circuit for the rotary magnet 28, whereupon the wipers are started rotating in search of an idle trunk line. As is well known, the rotary magnet interrupts its own circuit and also the locking circuit of the test relay 33 at every energization, the contacts in the latter circuit, however, being short circuited by the test wiper 24 while passing over busy or grounded test contacts. As soon, therefore, as the test wiper 24 arrives at an ungrounded test contact the test relay 33 falls back and opens the circuit of the rotary magnet, thereby bringing the wipers 23 and 25 to rest upon contacts which are terminals of an idle trunk line, represented in this case by conductors 71 and 73. As a further result of the deenergization of test relay 33, a circuit is completed for the line switching relay 29, which latter relay, upon energizing, disconnects the extended line conductors 1 and 2 from the line relay 26 and further extends them by way of wipers 23 and 25 and trunk conductors 71 and 73 to the double wound line relay 37 of the repeater F.

An energizing circuit for the line relay 37 may now be traced as follows: ground at G²¹, right hand winding of relay 37, contact springs 59 and 60, trunk conductor 73, subscriber's loop, trunk conductor 71, contact springs 57 and 56, and left hand winding of relay 37 to battery B. Line relay 37, upon attracting its armature, completes a circuit for slow acting relay 38 as follows: ground at G⁴, contact springs 49 and 48, and winding of relay 38 to battery B. Relay 38, upon energizing, completes a holding circuit extending back to the selector E and the line switch C over the following path: ground at G⁶, contact springs 54 and 53, conductor 72, and wiper 24 to wire junction 202, where the circuit divides, one branch extending by way of contact springs 75 and winding of line switching relay 29 to battery B, and the other branch extending by way of contact 74, contact springs 76, contact 20, spring 16, and holding winding 12 of line switch C to battery B.

Relay 38, in addition to closing the hold-

ing circuit just described, prepares a circuit for relay 64 by closing contact springs 52, and also completes a circuit including the left hand winding of relay 62 as follows: 5 ground at G^6 , contact springs 54 and 55, and left hand winding of relay 62 to battery B. It should be mentioned at this point that the left hand winding of relay 62 is simply a polarizing winding, and may be of 10 German silver wire. Owing to its high resistance and comparatively few turns the polarizing winding does not produce a sufficient magnetizing effect in the core of relay 62 to enable it to attract its armature. 15 Returning now to the line relay 37, an additional function performed by this relay is the closure of a circuit including the line relay 80 of the selector E' in the distant exchange. This circuit may be traced as follows: ground at G^8 , lower winding of relay 20 80, contact springs of line switching relay 29^a, trunk conductor 79, contact springs 47, contact springs 69 and 70, winding of impedance coil 63, right hand winding of relay 62, contact springs 66 and 67, trunk conductor 25 78, contact springs of line switching relay 29^a, and upper winding of relay 80 to battery B'. Line relay 80, upon energizing completes a circuit for slow acting relay 30 30^a, which relay, upon attracting its armature, prepares circuits for the vertical and rotary magnets 27^a and 28^a, all in a well known manner. It will be observed that the relay 62 of the repeater F now has 35 current flowing in its right hand winding as well as in its left hand winding. The direction of current flow in the former winding however, is such that its magnetizing effect opposes that of the polarizing winding; therefore the relay 62 remains inoperative. 40

The subscriber at substation A may now operate his dial in accordance with the second digit of the desired number resulting 45 in this case in a corresponding number of deenergizations of relay 37 of the repeater F. At each deenergization relay 37 separates contact springs 47, thereby reproducing the interruptions of its circuit in the 50 circuit of the line relay 80 of the selector E'. It follows that the selector E' will be operated through the medium of its line relay 80 to raise its wipers 71^a, 72^a and 73^a, until they stand opposite the horizontal level 55 of contacts which are terminals of trunk lines extending to the desired group of subscribers' lines; after which the wipers will be automatically rotated to select an idle one of these trunk lines, assumed to be in 60 this case the trunk line extending to the connector H (Fig. 3).

The operation of selector E' is substantially the same as that of selector E and need not be described in full. Upon the 65 energization of the line switching relay 29^a

after the selecting operation above mentioned, a circuit is completed for the line relay 82 of the connector H over the following path: ground at G^{22} , lower winding of relay 82, contact springs 211 and 212, conductor 114, wiper 73^a, contact springs of line switching relay 29^a, conductor 79, contact springs 47, contact springs 69 and 70, impedance coil 63, right hand winding of relay 62, contact springs 66 and 67, conductor 78, upper contact springs of line switching relay 29^a, wiper 71^a, conductor 113, contact springs 213 and 214, and upper winding of relay 82 to battery B'. Line relay 82, upon energizing, completes an energizing circuit for slow acting relay 85 which relay, upon attracting its armature, prepares a circuit for the vertical magnet in the well known manner and also completes a holding circuit for the selector E' as follows: ground at G^{10} , contact springs 91, conductor 92, wiper 72^a, contact springs 75^a, and winding of line switching relay 29^a to battery B'. 80 85 90

It will be well to return at this point to the repeater F and note its operation during impulses. At the first deenergization of relay 37 at the beginning of a series of impulses or interruptions of its circuit, a circuit is completed for the slow acting relay 64 as follows: ground at G^4 , contact springs 49 and 50, contact springs 52, and winding of relay 64 to battery B. Relays 38 and 64, being slow acting relays, retain their armatures in an operated position during a series of impulses. At the end of each series of impulses relay 64 deenergizes. In its operated position, relay 64 disconnects the trunk conductors 78 and 79 from the conductors 221 and 222, respectively, and from the windings in bridge thereof, and connects them over a different path which includes only the contact springs 47 of relay 37 and contact springs 68 and 69 of relay 64. In this way the impedance coil 63 and winding of relay 62 are excluded from the controlling circuit of line relay 80 (and later of line relay 82) while transmitting operating impulses. During this time also the right hand winding of relay 62 is short circuited by the closure of contact springs 65 and 66 to prevent its possible operation due to discharge of condensers 43 and 44. Inasmuch as the loop including the condensers 43 and 44 and the impedance 63 is in multiple with the subscribers' loop while sending impulses, the condensers should be of moderate capacity so as not to interfere with the operation of relay 37. 110 115 120 125

The subscriber at substation A may now operate his dial in accordance with the next digit of the desired number resulting as before in deenergization of the line relay 37 of the repeater F. Relay 37, through the medium of contact springs 47, reproduces the 130

5 interruptions of its circuit in the circuit of line relay 82 of the connector H. At each deenergization the line relay 82 sends an impulse from ground at G⁹ through the relay 93 and vertical magnet 83 in series, side switch wiper 117 being in its first position. The vertical magnet, in response to these impulses, steps up the shaft until the wipers 88, 89, and 90 stand opposite the horizontal level 10 in which are located contacts which are terminals of the line of substation A'. Relay 93, being slow acting, retains its armature during a series of impulses and maintains an energizing circuit for the private 15 magnet 95. At the end of the series of impulses relay 93 and private magnet 95 both deenergize, the latter controlling the side switch wipers in the usual manner to advance them to their second position.

20 The apparatus is now ready for the transmission of the final series of impulses by the same process as before. Side switch wiper 117 being in its second position, the line relay 82 now sends impulses to the rotary magnet 84 and the relay 93 in series, whereby the wipers 88, 89, and 90 are rotated until they stand upon contacts 231, 232, and 233, which are terminals of the line of substation A'. The private magnet is 25 controlled as before by relay 93, whereby the side switch wipers are advanced to their third position (it being assumed that the called line was idle).

As side switch wiper 118 comes into its 30 third position a circuit is completed from ground at G¹¹, by way of side switch wiper 118, wiper 89, contact 232, and holding winding 110 of line switch C' to battery B'. Upon energizing, the winding 110 attracts 35 the cut off armature of line switch C', thereby disconnecting the lines of substation A' from their connections in line switch C'. Ground potential is also placed upon the 40 multiples of contact 232 in the banks of other connectors, thereby making the line of 45 substation A' busy to other calls.

By the engagement of side switch wipers 115 and 116 with their third position contact points, the line conductors 113 and 114 are 50 extended through to the wipers 88 and 90, now in engagement with the line terminals of the desired line. By the engagement of side switch wiper 117, with its third position contact point a circuit is completed for 55 the ringing relay which circuit includes the interrupter 103. The ringing relay thereupon is operated intermittently to project ringing current out over the line of substation A' to signal the called subscriber.

60 The required connection has now been completed. It remains to be shown how the response of the called subscriber will bring about the desired circuit changes at the repeater F. When the subscriber at substation A' removes his receiver in response to

the ringing of his bell an energizing circuit is completed in the well known manner for the double wound back bridge relay 87 (ringing relay 102 being momentarily deenergized). Upon attracting its armature 70 relay 87 completes an initial energizing circuit for the ring cut-off relay 104 as follows: ground at G¹¹, side switch wiper 118, contact springs 107, and winding of relay 104 to battery B'. Relay 104 upon energizing, 75 opens the ringing relay circuit at contact springs 105 and also locks itself by closing contact springs 100.

As an additional result of the energization of back bridge relay 87 the line conductors 113 and 114 are reversed as regards their connection with the windings of relay 82. It follows that the direction of current flow in the previously described circuit including the right hand winding 85 of relay 62 (repeater F) will be reversed. Since the two windings of relay 62 now assist each other, relay 62 attracts its armature, thereby completing the following circuit: ground at G⁵, contact springs 51, and 90 winding of relay 39 to battery B. Relay 39, upon energizing, reverses the conductors 71 and 73, as regards their connections with the windings of relay 37 and at the same time inserts the windings of relay 40 in 95 series with the windings of relay 37. The energizing circuit of relays 37 and 40 may now be traced as follows: ground at G²¹, right hand winding of relay 37, upper winding of relay 40, conductor 71, previously 100 traced circuit through subscriber's loop, conductor 73, lower winding of relay 40, and left hand winding of relay 37 to battery B. Upon energizing, relay 40 connects the condensers 41 and 42 in multiple, respectively, 105 with condensers 43 and 44. Condensers 41 and 42 may be and preferably are of large capacity. Relay 40 is preferably of high impedance and its resistance should be regulated so that the combined resistance of relays 40 110 and 37 is suited to the transmitter current requirements of the average substation such as substation A. It may be mentioned that the limitation of the resistance of relay 40 is only necessary where the repeater is required to supply transmitter current to the 115 calling substation. Where this is not a feature of the operation relay 40 may be of much higher resistance.

Conversation between the calling and 120 called subscribers may now proceed, the voice currents taking the path shown by the heavy conductors.

When the conversation is finished both 125 subscribers will replace their receivers. By the hanging up of the receiver at substation A the energizing circuit of relays 37 and 40 of repeater F are broken. Relay 37, upon deenergizing, breaks the energizing circuit of relay 38 and the energizing cir- 130

cuit of line relay 32 of the connector H. As a result of the deenergization of relays 38 and 82 the previously described holding circuits of line switch C, selector E, and selector E' are broken and all the apparatus, including the connector H, is released and restored to normal position in the well known manner.

Had the called line been busy when called, 10 the side switch wipers of the connector H would have been locked in their second position immediately after the transmission of the final impulse in order to prevent connection with the called line and to facilitate the application of the busy tone to the calling line. Upon receiving the busy signal 15 the calling subscriber replaces his receiver, whereupon the apparatus is restored to normal as before mentioned.

20 It will be seen from the foregoing that I have devised a simple and efficient improvement in repeaters of the general type disclosed herein, whereby the impedance of the controlling relay bridge of such repeaters may be increased and whereby the normally connected trunk condensers of such repeaters may have other condensers connected in multiple with them, all for the purpose of providing a more efficient talking circuit.

25 While I have described in the foregoing a certain specific embodiment of my invention, I do not wish to be held strictly to the exact form disclosed, for various adaptations will no doubt suggest themselves to persons skilled in the art. I desire, therefore, to include and have protected by Letters Patent all forms and modifications of my invention which may come within the 30 scope of the appended claims.

What I claim as my invention is:

1. In a telephone system, a trunk line, a repeater in said trunk for repeating impulses over the same, a bridge for said repeater consisting of a relay and means for automatically adding another relay in series with said first relay to increase the impedance of said bridge.

2. In a telephone system, a trunk line, a repeater in said trunk for repeating impulses over the same, capacity in said trunk, and means for automatically increasing said capacity.

3. In a telephone system, a trunk line, a repeater in said trunk for repeating impulses over the same, capacity in said trunk at said repeater, and means controlled by said repeater for increasing said capacity.

4. In a telephone system, a trunk line, a repeater in said trunk for repeating impulses over the same, impedance and capacity in said trunk, and automatic means for increasing said impedance and capacity.

5. In a telephone system, a trunk line,

a repeater in said trunk for repeating impulses over the same, impedance and capacity in said trunk, and automatic means for first increasing said impedance and for then increasing said capacity.

6. In a telephone system, a trunk line, a repeater in said trunk for repeating impulses over the same, a front bridge and a back bridge for said repeater, means for increasing the resistance of said front bridge and means for shunting the resistance of said back bridge.

7. In a telephone system, a called line, a trunk line, a repeater comprising a relay in said trunk for repeating impulse, over the same, a bridge for said repeater, and means for automatically adding another relay in series with said first relay to increase the impedance of said bridge, said means controlled by the called line.

8. In a telephone system, a called line, a trunk line, a repeater in said trunk for repeating impulses over the same, capacity in said trunk, means for increasing the capacity of said trunk controlled by the called line.

9. In a telephone system, a called line, a trunk line, a repeater in said trunk for repeating impulses over the same, capacity in said trunk at said repeater, means controlled by said repeater for increasing the capacity of said trunk, said means controlled by the called line.

10. In a telephone system, a called line, a trunk line, a repeater in said trunk for repeating impulses over the same, impedance and capacity in said trunk, and means for increasing the impedance and capacity controlled by the called line.

11. In a telephone system, a called line, a trunk line, a repeater in said trunk for repeating impulses over the same, impedance and capacity in said trunk, means for first increasing said impedance and for then increasing said capacity controlled by the called line.

12. In a telephone system, a called line, a trunk line, a repeater in said trunk for repeating impulses over the same, impedance and capacity in said trunk, means for increasing said impedance controlled by the called line, and means controlled by said impedance for increasing said capacity.

13. In a telephone system, a called line, a trunk line, a repeater in said trunk for repeating impulses over the same, a front bridge and a back bridge for said repeater, said bridges having impedance, means controlled by said called line for increasing the impedance of said front bridge, and means for removing the impedance of said back bridge.

14. In a telephone system, a called line, a trunk line, a repeater in said trunk for

repeating impulses over the same, a front bridge and a back bridge for said repeater, said bridges having impedance, means for increasing the impedance of said front bridge, and means controlled by said calling line for removing the impedance of said back bridge.

15. In a telephone system, a called line, a trunk line, a repeater in said trunk for repeating impulses over the same, a front bridge and back bridge for said repeater, means controlled by the calling line, for increasing the resistance of said front bridge and means for shunting the resistance of said back bridge.

16. In a telephone system, a calling line, a trunk line, a repeater in said trunk for repeating impulses over the same, a front bridge and a back bridge for said repeater, means for increasing the resistance of said front bridge, and means controlled by the calling line for shunting the resistance of said back bridge.

17. In a telephone system, a central source of battery current for operating and talking purposes, a trunk line, a repeater in said trunk for repeating impulses over the same, a bridge for said repeater, and means responsive to the reversal of said battery current for increasing the impedance of said bridge.

18. In a telephone system, a central source of battery current for operating and talking purposes, a trunk line, a repeater in said trunk for repeating impulses over the same, capacity in said trunk, and means responsive to the reversal of said battery current for increasing the capacity of said trunk.

19. In a telephone system, a central source of battery current for operating and talking purposes, a trunk line, a repeater in said trunk for repeating impulses over the same, capacity in said trunk at said repeater, and means controlled by said repeater for increasing the capacity of said trunk responsive to the reversal of battery current.

20. In a telephone system, a central source of current for operating and talking purposes, a trunk line, a repeater in said trunk for repeating impulses over the same, impedance and capacity in said trunk, means responsive to the reversal of said battery current for increasing said impedance and capacity.

21. In a telephone system, a central source of battery current for operating and talking purposes, a trunk line, a repeater in said trunk for repeating impulses over the same, impedance and capacity in said trunk, and means responsive to the reversal of said battery current for first increasing said impedance and for then increasing said capacity.

22. In a telephone system, a central source

of battery current for operating and talking purposes, a trunk line, a repeater in said trunk for repeating impulses over the same, impedance and capacity in said trunk, means responsive to the reversal of said battery current for increasing said impedance, and means controlled by said impedance for increasing said capacity.

23. In a telephone system, a central source of battery current for operating and talking purposes, a trunk line, a repeater in said trunk for repeating impulses over the same, a front bridge and a back bridge for said repeater, said bridges having impedance, means responsive to the reversal of said battery current for increasing the impedance of said front bridge, and means for removing the impedance of said back bridge.

24. In a telephone system, a central source of battery current for operating and talking purposes, a trunk line, a repeater in said trunk for repeating impulses over the same, a front bridge and a back bridge for said repeater, means responsive to the reversal of said battery current for increasing the resistance of said front bridge, and means for removing the impedance of said back bridge.

25. In a telephone system, a trunk line, a repeater in said trunk for repeating impulses over the same, a front bridge comprising a line relay for said repeater, a second and a third relay for said repeater, means controlled by said second relay for reversing the connections to said line relay and for including said third relay in serial relation therewith.

26. In a telephone system, a trunk line, a repeater in said trunk for repeating impulses over the same, a front bridge comprising a line relay for said repeater, a second and a third relay for said repeater, means controlled by said second relay for reversing the connections to said line relay and for including said third relay in serial relation therewith, condensers in said trunk line, other condensers associated with said trunk line, and means controlled by said third relay for including said other condensers in multiple with said first mentioned condensers.

27. In a telephone system, a trunk line, a repeater in said trunk for repeating impulses over the same, a front bridge and a back bridge for said repeater across said trunk, a relay in said front bridge, condensers between said bridges, and means controlled by said back bridge for changing the relation of said front bridge with respect to said trunk and for adding another relay in said front bridge.

28. In a telephone system, a trunk line, a repeater in said trunk for repeating impulses over the same, a front bridge and a back bridge for said repeater across said

trunk, a relay in said front bridge, condensers between said bridges, and means controlled by said back bridge for reversing the connections of said relay with respect to 5 said trunk and for including another relay in said front bridge.

29. In a trunking system, a line, a trunk for setting up a connection with said line, capacity in said trunk, and automatic means 10 for varying the said capacity.

30. In a trunking system, a line, a trunk for setting up a connection with said line, capacity in said trunk, and automatic means for varying the said capacity, said automatic 15 means controlled for that purpose by said line.

31. In a trunking system, a line, a trunk for setting up a connection with said line, capacity in said trunk, automatic means for 20 varying the said capacity, said automatic means controlled for that purpose by said line, another line, and means for connecting said trunk and said other line.

32. In a trunking system, a line, a trunk 25 for setting up a connection with said line, capacity in said trunk, automatic means for varying the said capacity, said automatic means controlled for that purpose by said line, another line, and means for connecting 30 said trunk and said other line, whereby said two lines may be connected.

33. In a trunking system, a line, a two-conductor trunk for setting up a connection with said line, capacity in said trunk conductors, and automatic means for varying 35 the said capacity.

34. In a trunking system, a line, a two-conductor trunk for setting up a connection with said line, capacity in said trunk conductors, and automatic means for varying 40 the said capacity, said automatic means controlled for that purpose by said line.

35. In a trunking system, a line, a two-conductor trunk for setting up a connection 45 with said line, capacity in said trunk conductors, automatic means for varying the said capacity, said automatic means controlled for that purpose by said line, another line, and means for connecting said trunk 50 and said other line.

36. In a trunking system, a line, a two-conductor trunk for setting up a connection with said line, capacity in said trunk conductors, automatic means for varying 55 the said capacity, said automatic means controlled for that purpose by said line, another line, means for connecting said trunk and said other line, whereby said two lines may be connected.

60 37. In a trunking system, a line, a two-conductor link for setting up a connection with said line, capacity in one of said conductors, an impedance-bridge across said 115 conductors, and automatic means for varying said capacity and the impedance of said bridge, said automatic means controlled for that purpose by said line, another line, and

ing said capacity and the impedance of said bridge.

38. In a trunking system, a line, a two-conductor link for setting up a connection with said line, capacity in one of said conductors, an impedance-bridge across said 70 conductors, and automatic means for varying said capacity and the impedance of said bridge, said automatic means controlled for that purpose by said line.

39. In a trunking system, a line, a two-conductor link for setting up a connection with said line, capacity in one of said conductors, an impedance-bridge across said 75 conductors, automatic means for varying said capacity and the impedance of said bridge, said automatic means controlled for that purpose by said line, another line, and means for connecting said link and said other line.

40. In a trunking system, a line, a two-conductor link for setting up a connection with said line, capacity in one of said conductors, an impedance-bridge across said 80 conductors, automatic means for varying said capacity and the impedance of said bridge, said automatic means controlled for that purpose by said link, another line, and means for connecting said link and said other line, whereby said two lines may be connected.

41. In a trunking system, a line, a two-conductor link for setting up a connection with said line, capacity in each of said conductors, an impedance-bridge across said 90 conductors, and automatic means for varying said capacity and the impedance of said bridge.

42. In a trunking system, a line, a two-conductor link for setting up a connection with said line, capacity in each of said conductors, an impedance-bridge across said 105 conductors, and automatic means for varying said capacity and the impedance of said bridge, said automatic means controlled for that purpose by said line.

43. In a trunking system, a line, a two-conductor link for setting up a connection with said line, capacity in each of said conductors, an impedance-bridge across said 115 conductors, automatic means for varying said capacity and the impedance of said bridge, said automatic means controlled for that purpose by said line, another line, and means for connecting said link and said other line.

44. In a trunking system, a line, a two-conductor link for setting up a connection with said line, capacity in each of said conductors, an impedance-bridge across said 120 conductors, automatic means for varying said capacity and the impedance of said bridge, said automatic means controlled for that purpose by said line, another line, and

means for connecting said link and said other line, whereby said two lines may be connected.

45. In a trunking system, a line, a two-conductor link for setting up a connection with said line, a relay bridged across said link for controlling the same, another relay, automatic means for inserting said other relay in said bridge, capacity in one of said conductors, and means controlled by one of said relays for varying said capacity.

46. In a trunking system, a line, a two-conductor link for setting up a connection with said line, a relay bridged across said link for controlling the same, another relay, automatic means for inserting said other relay in said bridge, capacity in one of said conductors, and means controlled by one of said relays for varying said capacity, said automatic means controlled for that purpose by said line.

47. In a trunking system, a line, a two-conductor link for setting up a connection with said line, a relay bridged across said link for controlling the same, another relay, automatic means for inserting said other relay in said bridge, capacity in one of said conductors, means controlled by one of said relays for varying said capacity, said automatic means controlled for that purpose by said line, another line, and means for connecting said link and said other line.

48. In a trunking system, a line, a two-conductor link for setting up a connection with said line, a relay bridged across said link for controlling the same, another relay, automatic means for inserting said other relay in said bridge, capacity in one of said conductors, means controlled by one of said relays for varying said capacity, said automatic means controlled for that purpose by said line, another line, and means for connecting said link and said other line, whereby said two lines may be connected.

49. In a trunking system, a line, a two-conductor link for setting up a connection with said line, a relay bridged across said link for controlling the same, another relay, automatic means for inserting said other relay in said bridge, capacity in one of said conductors, means controlled by one of said relays for varying said capacity, said automatic means controlled for that purpose by said line, another line, and means for connecting said link and said other line, whereby said two lines may be connected, said first relay controlled over said other line.

50. In a trunking system, a line, a two-conductor link for setting up a connection with said line, a relay bridged across said link for controlling the same, another relay, automatic means for inserting said other relay in said bridge, capacity in said link, and means controlled by one of said relays for varying said capacity.

51. In a trunking system, a line, a two-conductor link for setting up a connection with said line, a relay bridged across said link for controlling the same, another relay, automatic means for inserting said other relay in said bridge, capacity in said link, and means controlled by one of said relays for varying said capacity, said automatic means controlled for that purpose by said line.

52. In a trunking system, a line, a two-conductor link for setting up a connection with said line, a relay bridged across said link for controlling the same, another relay, automatic means for inserting said other relay in said bridge, capacity in said link, means controlled by one of said relays for varying said capacity, said automatic means controlled for that purpose by said line, another line, and means for connecting said link and said other line.

53. In a trunking system, a line, a two-conductor link for setting up a connection with said line, a relay bridged across said link for controlling the same, another relay, automatic means for inserting said other relay in said bridge, capacity in said link, means controlled by one of said relays for varying said capacity, said automatic means controlled for that purpose by said line, another line, and means for connecting said link and said other line, whereby said two lines may be connected.

54. In a trunking system, a line, a two-conductor link for setting up a connection with said line, a relay bridged across said link for controlling the same, another relay, automatic means for inserting said other relay in said bridge, capacity in said link, means controlled by one of said relays for varying said capacity, said automatic means controlled for that purpose by said line, another line, and means for connecting said link and said other line, whereby said two lines may be connected, said first relay controlled over said other line.

55. In a telephone system, a first circuit, a second circuit, a relay in said first circuit, a relay in said second circuit, condensers for inductively connecting said circuits, other condensers, and means under the control of said second relay for connecting said other condensers in multiple with said first condensers.

56. In a telephone system, a first circuit, a second circuit, a relay in said first circuit, a relay in said second circuit, condensers for inductively connecting said circuits, other condensers, means under the control of said second relay for increasing the impedance of said first circuit, and for connecting said other condensers in multiple with said first condensers.

57. In a telephone system, a first circuit, a second circuit, a relay in said first circuit, a relay in said second circuit, condensers for

relay in said second circuit, condensers for inductively connecting said circuits, means under the control of said second relay for increasing the impedance of said first circuit, means whereby interruptions of said first circuit are repeated in said second circuit through the medium of said first relay, and means under the control of said first relay for closing said second circuit over a new path to the exclusion of said second relay, said last means effective during the transmission of said interruptions.

69. In a telephone system, a first circuit, a second circuit, a relay in said first circuit, a relay in said second circuit, condensers for inductively connecting said circuits, other condensers, means under the control of said second relay for connecting said other condensers in multiple with said first condensers, means whereby interruptions of said first circuit are repeated in said second circuit through the medium of said first relay, and means under the control of said first relay for closing said second circuit over a new path to the exclusion of said second relay, said last means effective during the transmission of said interruptions.

70. In a telephone system, a first circuit, a second circuit, a relay in said first circuit, a relay in said second circuit, condensers for inductively connecting said circuits, other condensers, means under the control of said second relay for increasing the impedance of said first circuit, and for connecting said other condensers in multiple with said first condensers, means whereby interruptions of said first circuit are repeated in said second circuit through the medium of said first relay, and means under the control of said first relay for closing said second circuit over a new path to the exclusion of said second relay, said last means effective during the transmission of said interruptions.

71. In a telephone system, a first circuit, a second circuit, relays in said first circuit having a certain impedance, a relay in said second circuit, condensers for inductively connecting said circuits, a source of current for said circuits, and means under the control of said second relay for increasing the impedance of said first circuit without removing any of the relays initially included therein, said second relay normally inoperative.

72. In a telephone system, a first circuit, a second circuit, a relay in said first circuit, a relay in said second circuit, condensers for

inductively connecting said circuits, a source of current for said circuits, other condensers, and means under the control of said second relay for connecting said other condensers in multiple with said first condensers, said second relay normally inoperative. 60

73. In a telephone system, a first circuit, a second circuit, a relay in said first circuit, a relay in said second circuit, condensers for inductively connecting said circuits, a source of current for said circuits, other condensers, means under the control of said second relay for increasing the impedance of said first circuit, and for connecting said other condensers in multiple with said first condensers, said second relay normally inoperative. 65 70

74. In a telephone system, a first circuit, a second circuit, a relay in said first circuit, a relay in said second circuit, condensers for inductively connecting said circuits, a source of current for said circuits, means under the control of said second relay for increasing the impedance of said first circuit, said second relay normally inoperative, and means associated with said second circuit for reversing the direction of current flow therein for operating said second relay. 75 80 85

75. In a telephone system, a first circuit, a second circuit, a relay in said first circuit, a relay in said second circuit, condensers for inductively connecting said circuits, a source of current for said circuits, other condensers, means under the control of said second relay for connecting said other condensers in multiple with said first condensers, said second relay normally inoperative, and means associated with said second circuit for reversing the direction of current flow therein for operating said second relay. 90 95

76. In a telephone system, a first circuit, a second circuit, a relay in said first circuit, a relay in said second circuit, condensers for inductively connecting said circuits, a source of current for said circuits, other condensers, means under the control of said second relay for increasing the impedance of said first circuit, and for connecting said other condensers in multiple with said first condensers, said second relay normally inoperative, and means associated with said second circuit for reversing the direction of current flow therein for operating said second relay. 100 105 110

Signed by me at Chicago, Illinois, this 2nd day of Feb., 1916.

TALBOT G. MARTIN.
